UNITED STATES PATENT OFFICE.

FRANK B. DICKINSON, OF ELMIRA, NEW YORK.

BELT-GUIDE.

1,280,682.

Specification of Letters Patent.

Patented Oct. 8, 1918.

Application filed April 11, 1918. Serial No. 227,899.

To all whom it may concern:

Be it known that I, FRANK B. DICKINSON, a citizen of the United States, residing at Elmira, in the county of Chemung and State 5 of New York, have invented certain new and useful Improvements in Belt-Guides, of which the following is a specification.

My invention relates to improvements in belt guides and is particularly constructed 10 and adapted for the purpose of guiding the belt used in connection with a Ford automobile for operating the fan which draws the outside air through the radiator and forces the same over the engine cylinders.

15. The objects of my invention are:

First, to construct a guide of the character above indicated which can be quickly and readily applied to the standard parts of a Ford car without in any way affecting the 20 installation or interrupting the existing arrangements of the present form of engine and its auxiliary mechanism.

Second, to construct a device of the character indicated which consists of a minimum 25 number of parts capable of being easily and cheaply manufactured and all the parts are in sight so as to enable the same to be readily installed, inspected, adjusted or repaired.

Third, to construct a belt guide which will 30 positively retain the belt on its coöperating pulley or pulleys, and will be enabled to spring away with the belt without offering too great a resistance, thereby avoiding undue wear on the edges of the belt or impair 35 the constant and uniform lineal speed of said belt.

Fourth, other objects and advantages of the invention and its mode of application and operation will appear from the detailed 40 description to be hereinafter given.

The invention consists of structural characteristics and relative arrangement of the several elements which will be hereinafter more fully described and particularly pointed out in the appended claims.

In the drawings, in which similar reference characters indicate the same parts throughout the several figures:

Figure 1 is a front end view of a Ford 50 engine, showing the engine and fan in dotted lines and the relation of my improved belt guide with respect to the same in full lines;

Fig. 2 is a section on line II—II of Fig. 1;

Fig. 3 is a perspective view of a locking

washer used in connection with the belt 55 guide, and

Fig. 4 is a side view of a modified form of the belt guide.

Referring to Figs. 1, 2 and 3, 10 represents the usual Ford engine on its base plate 60 11. 12 is the shaft of the engine carrying the lower fan belt pulley 13, while 14 is the upper fan belt pulley supported from an adjustable bracket 15, secured to the engine frame, and which is connected with and 65 rotates the fan 10'. The timer controlling the ignition of the cylinders of the engine is represented by 17, and a bolt 18 is provided for securing the cover of the timer 17 to its casing. The constructions so far referred to are the standard parts of a Ford engine and form no part of the present invention.

The improved belt guide 19 comprising my invention, is preferably formed of 75 round spring steel wire bent into U-shape, as shown having an eye 20 formed at one end which is adapted to snugly fit around the bolt 18, as clearly shown in Figs. 1 and 2. The two fingers 21 and 21 of the belt guide 80 19 are bent over at their free ends at right angles and backward parallel to the fingers 19, as shown in Fig. 2, to form guideways or channels 22, 22, to receive and guide the belt 16, and keep the same from having ab- 85 normal movement along the length of the shaft 12, and run off the pulley 13 or 14. To prevent the fingers 21 and 21 of the belt guide 19 from spreading or disturbing their proper coöperative relation with each other 90 and the belt 16, there is provided a washer 23, as shown in Fig. 3, which is punched out from sheet metal with ears 24, 24, an opening 25, and extension 26. This washer 23, as shown in Fig. 3, is adjusted and arranged so 95 that the two ears 24, 24, embrace or abut against the outer edges of the fingers 21, 21 next to eye 20, and the bolt 18 is passed through the eye 20 and opening 25, after the belt 16 has been properly adjusted and dis- 100 posed in the channels or guides 22, 22 at the free ends of the fingers 21, 21, as previously explained. When the belt guide 19 and its washer 23 are positioned on the bolt 18, as shown in Figs. 1 and 2, the bolt 18 is screwed 105 into the cover of the timer 17 to firmly clamp and rigidly hold the reduced end or eye 20 of the belt guide 19 to the timer cas-

ing 17, and its guide or channel ends 22 in proper relation to the belt 16. The extension 26 on washer 23 is turned up against the side of the bolt head 27, as shown in Figs. 1 and 2, thereby acting as a lock and prevents the belt guide 19 from working loose from its fastened end or eye section 20, and preserve its proper relation with the belt 16. It will also be seen that the 10 two wings or lugs 24, 24 by embracing the two fingers 21, 21 prevent said fingers from spreading, and hence cause their channel or guide ends 22, 22 to frictionally engage the belt 16, thus the washer 23 not only 15 forms the function of a means to prevent a distortion of a section of the belt guide, but at the same time acts as a lock to avoid displacement of the adjusted position of the belt guide.

20 In the modified form shown in Fig. 4, the construction of the belt guide 19' is substantially the same as that shown in Figs. 1 and 2, except the eye 20' is formed by crossing the single piece of wire, and the fingers 21', 21', and channels or guide ends 22', 22', being of the same construction and operating in the same manner as disclosed with references to the form shown in Fig. 1. In the modification of the invention illustrated 25 in Fig. 4, no washer 23 is employed, if so desired, as the fingers 21', 21' normally tend to return to their set position.

From the foregoing description of the construction and relation of the parts of the invention, it will be readily seen that all the objects and advantages recited in the statement of invention are fully and efficiently carried out and the resiliency of the spring wire construction of the belt guide, when said guide comes in contact with the belt, permits said guide to compensate or spring away with the belt without offering injurious resistance thereto and cause the belt to wear on its edges. The belt guide 40 can also be quickly adjusted so as to always

properly guide the belt and maintain the belt on the driving pulley 13, secured to the engine shaft 12.

What I claim is:

1. A belt guide consisting of a single 50 wire strand bent to form an eye at one end and two separated fingers extending from said eye, each of said fingers having a channel section formed at its end adapted to receive and guide a belt.

2. A belt guide consisting of a single wire strand bent to form an eye at one end and two separated resilient fingers extending from said eye, each of said fingers having formed at its end a channel constructed 60 and arranged to receive and guide a belt.

3. A belt guide consisting of a single wire strand bent to form an eye at one end and two separated resilient fingers extending from said eye, each of said fingers having formed at its end a channel constructed 65 and arranged to receive and guide a belt, and a washer having an opening registering with the said eye and ears engaging the outer sides of the resilient fingers adjacent 70 to said eye section to prevent the fingers from spreading from each other.

4. A belt guide consisting of a single wire strand bent to form an eye at one end and two separated resilient fingers extending 75 from said eye, each of said fingers having formed at its end a channel constructed and arranged to receive and guide a belt, and a combined lock and washer having an opening registering with the said eye and 80 ears engaging the outer sides of the resilient fingers adjacent to said eye section to prevent the fingers from spreading from each other and a flexible extension adapted to be bent up from the washer and engage the 85 head of a bolt passed through said eye and opening.

In testimony whereof I affix my signature.

FRANK B. DICKINSON.
